UNITED STATES PATENT OFFICE.

RAFFAELE BACCELLIERI, OF PHILADELPHIA, PENNSYLVANIA.

FRUIT CRUSHER.

Application filed September 14, 1922. Serial No. 588,103.

To all whom it may concern:

Be it known that I, RAFFAELE BACCELLIERI, a citizen of the United States, residing at Philadelphia, in the county of Philadelphia and State of Pennsylvania, have invented 5 certain new and useful Improvements in Fruit Crushers, of which the following is a specification.

This invention relates to crushers and 10 graters and more particularly to fruit crushers of the rotary type.

In fruit crushers as heretofore constructed, the crushing rollers were provided with ribs, and these ribs intermesh and contact 15 in operation to drive one roller from the other and the fruit is crushed or mashed between surfaces and ribs of the rollers. This causes undue strain, wear and tear on the bearings and parts, undue mashing and 20 bruising of the fruit, especially when subjected to heavy work or duty and also interferes with the intermeshing and driving of the rollers, thus causing wedging of the rollers, injury to the parts necessitating repair 25 or replacements, and reduction in efficiency.

The object of the present invention is to provide a fruit crusher in which the rollers are positively driven and the surfaces of the rollers are brought in close proximity 30 without touching or pressing against each other, thus preventing injury to the crusher or bearings of the rollers and permitting easier operation, producing greater efficiency and larger capacity consistent with thorough 35 crushing or expressing of the juices from the fruit with light or heavy work.

These objects, and other advantageous ends which will be described hereinafter, I attain in the following manner, reference 40 being had to the accompanying drawings in which

Figure 1 is a plan view of the improved fruit crusher,

Figure 2 is a side elevation,

45 Figure 3 is a vertical longitudinal sectional view taken on the plane of the section line 3—3 of Figure 1,

Figure 4 is a horizontal longitudinal sectional view taken on the plane of the section lines 4—4 of Figures 2 and 3, and

50 Figure 5 is an enlarged perspective view of one of the crushing rollers.

In the drawings, 6 is a frame consisting of parallel side rails 7, and cross rails or bars 8 between the side rails. Side rails 7 are connected, as by bolts 9 seated in lon-

gitudinal recesses 10 in the outer faces of cross rails 8, so that the side rails are firmly held against the ends of the cross rails. The parts described are preferably of wood and metallic plates 11 are preferably disposed against the outer faces of the side rails and apertured to receive the bolts and bear the strain of pressure or stresses due to the connection and also the operation of the device as will be hereinafter described.

A hopper 12 is mounted upon the frame and rests upon portions of the side rails and the cross rails. Braces 13 firmly secure the hopper to the cross rails and the bottom of the hopper is open for the discharge of the fruit, such as grapes or other food to be crushed, fed to the rollers by the hopper. The ends of rails 7 may be cut out to provide handles 14 as one convenient means of 60 transportation and handling of the hopper or device, and whereby it may be placed upon or removed from over a barrel or other receptacle, when in use.

A plurality, preferably two, corrugated rollers 15 and 16, are journaled as by means of shafts or pivots 17 and 18 in side rails 7 parallel to each other and cross rails 8, and occupy substantially the entire cross sectional area of the discharge opening at the 65 bottom of the hopper. These rollers each preferably have four longitudinal ribs 19 with convex surfaces and intermediate longitudinal concavities 20 taken cross-sectionally. When the rollers are placed in position mounted as described, a rib of one roller extends into a concavity of the other roller but instead of interfitting, meshing, engaging or contacting, the rollers do not contact or touch but a space is left between the surface of the rib and the surface of the concavity. By this means, the rollers do not 70 depend upon contact or engagement to drive one from the other in the operation of the device, undue stresses on the parts are relieved, clogging, wedging or jamming, and injury to the parts prevented and the output of the machine increased as compared with the old construction.

A pinion 21 is fixed to an extended end of pivot 17 and a pinion 22 is secured to an extended end of adjacent pivot 18 and meshes with pinion 21. Pivot 18 extends through slots 23 in side rails 7 and plates 11, and have spring-pressed adjustable tension 75 bearings 24 including springs 25, movable blocks 26 and set screws 27 to adjust the ten-

sion of springs 25 and vary the relation of rollers 15 and 16 to each other. Roller 15 is fixed, and roller 16 may move or be adjusted without contact with roller 15 due 5 to the space between them, for the reasons above specified. The rollers may be suitably driven or rotated, and a crank handle 28 is shown fixed to pivot of roller 15 to rotate it and impart rotation to roller 16 through the 10 intermeshing pinions 21 and 22.

In the operation of the device, the fruit or other material to be crushed is placed in hopper 12 and the rollers are turned. The fruit drops into the depressions of the rollers 15 and is crushed between the co-acting surfaces by the extension of the ribs of the rollers into the concavities of each other roller, the crushed fruit being discharged from between the rollers and dropping into 20 a suitable receptacle upon which the device is adapted to be supported by the side rails of the frame. The device may be conveniently applied to or removed from upon the receptacle through the medium of the handles, but this arrangement may be varied 25 since the primary feature of the machine is the construction and relation of the rollers. By driving the rollers positively through operative connections between their pivots or 30 shafts, as by means of the pinions, I have found that the number of corrugations on the rollers may be reduced to a minimum, thus lending efficiency to the crushing oper-

ation or out-put and decreasing the cost of production of the rollers owing to their 35 simplification.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claim.

Having thus described my invention, what I claim as new and desire to secure by Letters Patent is:—

A fruit crusher of the class described including parallel side rails, cross bars between the side rails and having longitudinally recessed portions, connecting members mounted in the recesses, a hopper resting on the cross bars and portions of the side rails, said hopper having a discharge opening and 50 provided with means of attachment to the cross bars, and crushing elements within the hopper at the discharge opening.

In testimony whereof I have signed my name to this specification in the presence of 60 two subscribing witnesses.

RAFFAELE BACCELLIERI.
